COMPUTING COUNTER

Edward Wild, Hartford, Conn., assignor to Vee-
der-Root Incorporated, a corporation of Con-
necticut

Application June 17, 1937, Serial No. 148,720

11. Claims. (Cl. 235—144)

My invention relates to computing counters. It has among its objects to provide an improved counter adapted to indicate quantity and cost, as, for example, in dispensing gasoline. A further object of my invention is to provide such an improved counter of the removable counter unit type and having improved means whereby the assembly and removal of the counter units is markedly facilitated while also making possible the use of improved units. Another object is to provide such an improved construction having shutter mechanism for the several counters and improved connections for enabling the removal of any selected counter unit without requiring either the disconnection of the shutter mechanism or the removal of the same before the unit can be removed from the machine. A still further object is to provide an improved construction and arrangement of counter units, of shutter operating mechanism, and of driving and resetting mechanisms, whereby the above objects may be obtained. Still another object is to provide an improved and simplified construction wherein the elements are so disposed as to require a minimum of operating gearing connecting the same and to produce a very compact structure, all while still obtaining the above markedly increased facility in connecting or removing the several counter units and enabling the several elements of the drive and resetting mechanism to cooperate in an improved manner with the counting mechanism of each unit and the shutter mechanism therefor. A further object is to reduce the manufacturing costs and facilitate service in the field, by making possible the use of improved sub-assemblies including the several counter units and their resetting and shutter mechanisms and shutter operating mechanisms therefor, whereby these several mechanisms may cooperate with the driving and resetting mechanisms on the machine frame in an improved manner. These and other objects of my invention will, however, hereinafter more fully appear.

In the accompanying drawings, I have shown for purposes of illustration, one embodiment which my invention may assume in practice.

In these drawings:

Figure 1 is a perspective view of the complete counter, portions of the front cover plate being broken away to facilitate illustration;

Fig. 2 is a front elevation of the counter, the above cover plate being removed;

Fig. 3 is a top plan view of the construction shown in Figure 2;

Fig. 4 is a rear view of the construction shown in Figure 2;

Fig. 5 is a side elevation of the same construction, the view being taken from the right of Figure 2;

Fig. 6 is a section on line 6—6 of Figure 3, the ends of the counter units being shown in elevation and certain parts of the same being broken away, to facilitate illustration;

10 Fig. 7 is a sectional view on line 7—7 of Figure 2;

Fig. 7a is a detail perspective showing the swinging stop arm and latch mechanism;

Fig. 8 is a sectional view on line 8—8 of Figure 2;

Fig. 8a is a detail perspective of the shipper operating cam;

Fig. 9 is a sectional view on line 9—9 of Figure 2, the number wheels and certain of the connections thereto being shown in elevation;

Fig. 10 is a sectional view on line 10—10 of Figure 2;

Fig. 11 is a perspective view of the left hand cost counter unit;

25 Fig. 12 is an end view of the unit shown in Figure 11, the same being shown as meshing with a gear in the resetting train on the frame, and the counter resetting gear being broken away, the shutter operating member being shown in two positions;

Fig. 13 is a detail section on line 13—13 of Figure 12;

Fig. 14 is a like section on line 14—14 of Figure 12;

35 Fig. 15 is a vertical longitudinal section through the counter unit shown in Figure 11 and its support upon the frame;

Fig. 16 is a sectional view on line 16—16 of Figure 15;

40 Fig. 17 is a sectional view on line 17—17 of Figure 15;

Fig. 18 is a sectional view on line 18—18 of Figure 15;

Fig. 19 is a sectional view on line 19—19 of Figure 15;

45 Fig. 20 is a sectional view on line 20—20 of Figure 15;

Fig. 21 is a detail view of the resetting mechanism similar to Figure 2 and showing this mechanism in reset position, but showing a modified construction, the remainder of the mechanism being omitted to facilitate illustration;

50 Fig. 22 is a simplified view similar to Figure 21, showing the position of the parts in the first holding position of the no-reverse pawl;

Fig. 23 is a similar view showing the position of the parts when the pin is out of the notch in the cam;

Fig. 24 is a similar view showing the parts in their fourth holding position, the cooperating holding pawl also now being in holding position;

Fig. 25 is a similar view showing the position of the parts when the swinging stop member is swung into block engaging position;

Fig. 26 is a similar view showing the parts held by the holding pawl, the pin then being about to reenter the notch in the rotating cam;

Fig. 27 is a similar view showing the pin reentering the notch at the start of the reverse movement;

Fig. 28 is a similar view showing the parts just prior to the completion of the reverse movement at the end of resetting, and

Fig. 29 is a developed diagram of the resetting cam and of the resetting cycle of the mechanism shown in Figures 21 to 28.

In this illustrative construction, I have shown a computing counter of a usual type adapted to cooperate with a meter (not shown) and a variator (not shown) in a well known manner in measuring gasoline and indicating the cost thereof. Herein, (Figs. 1 and 4) it also comprises left and right hand quantity counters, generally indicated at 1 and 1a, respectively, driven directly from the meter, and left and right hand cost counter units, generally indicated at 2 and 2a, respectively, driven from the meter through the variator; the several counters being in the form of improved units constructed, arranged and cooperating with improved driving and resetting mechanism and having improved shutter and shutter operating mechanism on these units cooperating with said resetting mechanism in an improved manner, all as hereinafter more fully appears.

Referring first to the drive for the quantity counter units 1, 1a, both of these are driven from a vertical centrally located shaft 3 (Fig. 7) driven by the meter. As shown, this shaft is connected through a bevelled pinion 4 with a bevelled gear 5 fixed to a centrally located horizontal drive shaft 6. This shaft, in turn, is suitably journaled at its front end in a front frame member 7 extending across the several counter units and carrying the same, and journaled at its rear end in a supplementary narrower upstanding frame member 8 fixed at the top and bottom to rearwardly extending projections 9 and 10 on the frame member 7. Herein, a thin washer 11 is provided between the hub of the gear 5 and the frame 8, while the shaft 6 is slightly movable longitudinally in its journals. Also, the gear 5 is provided with a flange 12 (Fig. 8) on the opposite face of the same, forming a journal for a like cooperating flange on a shipper sleeve 13, which sleeve herein houses a coiled spring 14 acting between this shipper sleeve and the gear 5, within the flange 12 on the latter. As shown, the shipper sleeve 13 is journaled at its front end at 15 on the shaft 6, and is also provided with a bushing 16 on which is rotatably mounted a quantity counter driving member 17 having counter driving gear teeth 18 on its rear end, adapted to drive both quantity counters as hereinafter described, and also carrying a friction clutch element 19 on its front end. Herein, this member 17 also carries a radially extending stop or block 20 (Figs. 6 and 7) on a portion of intermediate diameter between the gear teeth 18 and the friction clutch element 19. This block

20, if desired, may be cast integrally with the member 17, but herein is carried on an annular member 21 suitably pour or otherwise cast into a corresponding annular groove in the member 17 between the portions 18 and 19 thereof. Cooperating with the friction clutch element 19 is a like element 22 disposed between the latter and the frame 7 and suitably fixed as at 23 to the shaft 6. Thus, when the elements 19 and 22 are connected, the quantity counter driving gear 18 will be driven from the meter driven shaft 3.

Meshing with opposite sides of the counter driving gear 18 are intermediate gears 24 and 25, herein carried on shafts 26 and 27 (Figs. 6 and 10). Of these, the shaft 26 is carried by the left hand quantity counter unit 1, while the shaft 27 is carried on the right hand quantity counter unit 1a; the shaft 27 being a long shaft extending the length of the counter unit 1a and journaled thereon in removable end journals 28, while the shaft 26 is a short or stub shaft located only at the front end of the unit 1 and journaled therein in a single like journal 29. Thus, it will be evident that with the driving gears 30 and 31 disposed on opposite ends of the counter units 1 and 1a and connected to the lowest order denominational order wheels thereof, the intermediate gear 24 on the unit 1 will mesh with the driving gear 30 at the front end of the counter unit 1, while the intermediate gear 25 will rotate its shaft 27 and a gear 32 on the rear end of that shaft and the unit 1a, which meshes with the gear 31 on the counter unit 1a. Accordingly, the counter mechanisms of each of these units 1, 1a will be driven from the meter driven shaft 3 through the gear 18 on the member 17 or disconnected from the shaft 3 depending upon the position of the shipper member 13. Moreover, it will be observed that when the shipper member 13 is moved longitudinally to disconnect these clutch elements 19, 22, i. e. to the right as shown in Figure 8, the gear 18 will remain connected with the lowest order wheels of both counters, through the train driven by the intermediates 24, 25. Also, the member 17 then will be freely rotatable on the shipper member 13, and the movement of the latter will compress the spring 14 in such manner as to force the hub of the gear 5 to the right (Fig. 8) and press the washer 11 against the adjacent shaft bearing on the frame 8 in such manner as effectually to brake the shaft 6 and the friction clutch driving element 22 thereon. Attention further is directed to the fact that the structure is such as to effect braking before the disconnection of the friction clutch elements 19, 22.

Referring next to the drive for the cost counter units 2, 2a, it will be observed that the same is generally similar to that just described. Here a shaft 35, corresponding to the shaft 3 but driven from the meter through the variator, is connected through a bevel pinion 36, corresponding to the pinion 4, with a bevel gear 37, corresponding to the gear 5. This gear 37 is herein fixed to the protruding end of a shaft 38, corresponding to the shaft 6, and similarly journaled in the frame members 7 and 8 and also similarly reciprocable in its journals. Here a collar 39 inside the frame member 8 corresponds to the hub of the gear 5, heretofore described, and is fixed to the shaft and provided with a washer 40, corresponding to the washer 11. Moreover, a like shipper sleeve 41 is provided having a coiled spring 41a, corresponding to the spring 14, but here acting against the end of collar 39. Further, the sleeve 41 car-

ries a member 42, corresponding to the member 17 and having corresponding gear-teeth 43 and a friction element 44, corresponding respectively to the gear teeth 18 and friction element 19 heretofore described. Also an intermediate member 45, corresponding to the member 21, and carrying a block 46 (Fig. 6), corresponding to the block 28, is also provided, while a driving friction element 47 corresponds to the friction element 22, and is similarly fixed to its shaft 38, the member 42 being journaled at 48 on the shipper 41 similarly to the member 17.

It will be also evident that the operation of this cost counter drive will be essentially similar to the quantity counter previously described, when the clutch elements 44, 47 are connected or disconnected. Further, the gear 43 (Fig. 9) is connected to intermediates 49 and 50, corresponding to intermediates 25 and 24, and these intermediates are carried on short and long shafts 51 and 52 mounted on the units 2, 2a and corresponding to shafts 26 and 27, while the gear 50 and a diagonally opposite gear 53 are connected to counter driving gears 54, 55 on the lowest order wheels of the units 2 and 2a, respectively. Thus, the lowest order wheels on the cost counter units 2, 2a are driven similarly to the corresponding wheels on the quantity counter units 1, 1a, when the proper clutch mechanism, herein including the elements 44, 47 is connected. Also, when these latter elements are disconnected, the collar 39 will press the washer 40 against the adjacent shaft bearing to brake the clutch driving element 47 and consequently the shaft 35 and the elements of the variator, the timing of the clutch and brake mechanism also being as heretofore described.

Operatively connected to actuate the shippers 13 and 41 is also improved shipper operating mechanism. This mechanism (Figs. 7 to 10, inclusive) includes a reciprocable shipper operating member 60 longitudinally reciprocable on a horizontal main reset shaft 61, disposed between the shafts 38 and 6 and also suitably journaled in the front and rear frames 7 and 8. Herein, this shipper operating member 60 is provided with usual forked ends 62 extending around the shipper members 13 and 41. One of these ends 62 engages a collar 63 on the shipper 13, while the other engages one of a pair of adjusting nuts 64 adjustable on a threaded portion 65 on the shipper 41. Also, the hub 67 of the member 60 is carried on a sleeve 66 in which the reset shaft 61 is freely rotatable. Further, it will be noted that the hub of the member 60, herein indicated at 67, is suitably bell-mouthed, as shown at 68, at its rear end in such manner as to permit a rocking motion of the member 60 relative to the sleeve 66. As shown in Figs. 7 and 10, the member 60 is also provided midway between its ends with oppositely projecting lateral extensions 69. Each of these, in turn, is bifurcated at 70 to receive a crowned roller 71 freely rotatable on a stationary stud 72. One end of this stud is also fixed to and enclosed within one of the bifurcations on the portion 69, while the other end projects into an aperture 73 in the portion 69 in such manner as to permit access to the bearing for the roller 70. Cooperating with these rollers 71 on opposite sides of the member 60 is a rotatable cam member 74, herein formed integral with the sleeve 66. Further, a hardened annular cam track 75 of suitable wear-resistant metal is seated in the face of the member 74 adjacent the members 71 and normally engages therewith. 75

As shown, this cam track 75 is also provided with diametrically opposite notches or wells 76 (Fig. 8) adapted to receive the rollers 71 in the normal position of the parts, so that rotation of the members 74 will automatically cause the rollers to pass out of the notches 76 and ride over the remaining surfaces of the member 74 which thus provide dwell surfaces. Here attention is also directed to the fact that a diagonally disposed yoke 77 is disposed in front of the rotatable member 74, which yoke is rigidly connected to the rear frame member 8 by arms 78, 79, respectively disposed above and below the lateral projections 80 (Figs. 9 and 10). Moreover, note that between the member 74 and the hub of this frame member 77 a suitable ball thrust bearing 80 is provided, the same herein being seated in the hub of the frame 77.

In operation, the shipper operating member 20 including the rollers 71, being loosely carried on the shaft 61 when the rollers 71 are in the wells or notches 76, it will be evident that when the rotary member 74 is rotated, the rollers 71 will be forced out of these notches in such manner as to force the member 60 back longitudinally on the sleeve 66 and, thereby, cause its end 62 to engage the collar 63 and nut 64. As a result, the springs 14 and 41a of the quantity counter and cost counter drives, respectively, will be compressed and, through the mechanism associated with the shippers 13 and 41, those drives will be braked and thereafter disconnected from the driving clutch elements 22, 47, as heretofore described. Moreover, it will be evident that by the adjustment of the nuts 64, one of which engages the end 62 of the shipper operating member 60 and the other of which forms a locking nut, it is possible to vary the adjustment as desired. Obviously, when the member 74 is reversely rotated, the parts will also be returned to their normal position wherein the rollers 71 are in the notches 76, under the action of the springs 14, 41a.

Operatively connected to the rotatable cam member 74 is also improved mechanism for rotating this member to control the shipper cooperating member 60 and, through the latter, control the braking of the quantity and cost counter drives and the connection of the friction clutches therein, as previously described. This mechanism includes a link 85 (Fig. 7) pivotally connected at its lower end at 86 to the back of the member 74 at a point slightly below one of the notches 76. At its upper end, this link is adjustably pivotally connected through an arcuate slot and bolt connection 87 (Figs. 4 and 8a) to a laterally extending arm 88. This arm, in turn, is journaled on the front frame 7 on a forwardly extending shaft 89 to the rear of which the arm 88 is pinned, while the front end of this shaft projects through and beyond the frame 7 and carries a toothed sector 90 (Figs. 2 and 7). This sector, in turn, cooperates with like teeth 91 on a pivoted controlling cam 92 pivoted on a forwardly protruding journal portion 93 on the frame 7, coaxial with the shaft 38. This swinging cam 92 is connected by a coiled spring 94 to the frame 7 in such manner that the cam 92 is biased to the position shown in Figure 2, the cam 92 herein being provided with an arm 95 to which this spring is connected and also adapted to engage a stop 96 on the front face of the frame 7 in the normal position of the parts illustrated. Further, note that the cam 92 is provided with a depending arm 97 carrying a

pin 98 receivable in a notch 99 in a rotating cam 100 fixed to and rotatable with the reset shaft 61 whenever that shaft is rotated during resetting; a suitable key (not shown) being connectible in an operating end 101 provided on the extremity of the shaft 61.

Assuming that the parts are in the position shown in Figure 2, following the completion of counting, it will be evident that when the shaft 61 is then rotated to effect resetting, the cam 92 will be moved in a well known manner. As its pin 98 rides out of the notch 99 onto the periphery of the cam 100, the cooperating teeth on the members 90, 92 move the member 90 to the right from the position shown in Figure 2, 15 and thereby rotate the shaft 89. Thus, through the link 85, the member 74 is rotated and, accordingly, the drives of the quantity and cost counters are braked as heretofore described, while the driven friction clutch elements 19 and 44 20 are also disengaged from the driving friction clutch elements 22 and 47. Attention here is further directed to the fact that this braking operation occurs in the first stages of movement of the cam 92, while it will also be evident that 25 as the latter returns to its normal position, illustrated in Figure 2, at the completion of resetting, the tooth member 90 will be reversely operated to reconnect the friction elements and release the brake in the last stages of resetting, i. e. as 30 the member 92 is moved reversely by its spring 94 after its pin 98 has reentered the notch 99 on the cam 100. In this connection, attention is also directed to the fact that while both drives 35 are braked at the beginning of the resetting operation and have their friction clutches disconnected shortly thereafter, at the end of the resetting operation, the friction clutches are first reconnected and the brakes thereafter released.

Operatively associated with the reset shaft 61, is also improved reset driving mechanism. This, as shown in Figs. 6, 7, and 8, includes a reset operating gear 105 suitably fixed to the reset shaft 61 and carried thereon, this gear being in rear of the front frame member 7 and in front of the driving elements 22 and 47 of the friction clutches, and also having a hub 106 thereon which, at its rear end, abuts the bearing support 77. Meshing with this gear 105 and on opposite sides thereof, are reset driving intermediates 107 and 108, each of which is journaled on the front frame member 7 on a short stud 109 (Figs. 6 and 10). Of these gears, the gear 107 meshes with reset driving gears 110 and 111 on the upper left hand cost counter unit 2 and the lower left hand quantity counter 1, respectively, while the gear 108 meshes with corresponding driving gears 112 and 113 on the upper right cost counter unit 2a and the lower quantity counter unit 1a. Also, these several reset operating gears 105, 110, 111, 112 and 113 are each connected through usual angular adjusting means 114 with the several reset shafts 115, 116, 117 and 118, respectively. The latter shafts being connected with the number wheels on the various counter units through usual cooperating pawl mechanism, hereinafter described, it will be evident that rotation of the gear 105 with the reset shaft 61, will simultaneously rotate the two intermediate gears 107 and 108 so that each of these will drive the two resetting gears on the counter units above and below the same, and thereby simultaneously effect resetting of all of the number wheels. Here, attention is also directed to the fact that these 75 gears 107 and 108 are so disposed as to permit

the reset driving gears 110, 111, 112 and 113 to be brought into mesh or moved out of mesh with these intermediate gears upon longitudinal movement of the several counter units 1, 1a, 2, 2a.

Operating in timed relation with respect to the reset operating gear 105 is also improved controlling mechanism. Herein, this mechanism includes the spring connected swinging cam 92 which, when released at the end of a resetting operation of the reset shaft 61, causes that shaft to be rotated reversely to rotate the several counter reset shafts 115 to 118, inclusive, through an angle of 45°, as the pin 98 returns into the notch 99 in the cam 100. Further, as in a usual construction, a no-reverse ratchet 120 is carried on the shaft 61 between the cam 100 and the front frame 7 and in rear of the cam 92 (Figs. 2 and 9). Cooperating with this ratchet 120 is also a no-reverse pawl 121 pivoted on the journal portion 93, heretofore described, and having usual depending arms 123 and 125 adapted to cooperate with portions of the ratchet 120 in a usual manner; this no-reverse pawl likewise being disposed in rear of the cam 92 above the ratchet 120, while a supplementary no-reverse or holding pawl 122 is also disposed beneath the ratchet 120 and likewise cooperates therewith in a usual manner. As shown, the no-reverse pawl 121 also has one of its arms 123 connected 30 through a coiled spring 124 to the frame, in such manner as to bias the pawl to the position shown in Figure 2, while the other arm 125 of this pawl is controlled by spring connected latch mechanism 126 pivoted at 127, having a projection 128 thereon adapted to underlie a cooperating projection 129 on the pawl arm 125. Further, this latch member 126 carries a pin 130 on its upper extremity adapted to cooperate with a nose-shaped cam portion 131 on the cam member 92. 35 The operation of the no-reverse pawl 121, the latch 126, and the supplementary holding pawl 122 is generally similar to that of corresponding parts disclosed and described in connection with the embodiment shown in Figs. 21 to 28. It may here be said that during a portion of the resetting operation of the reset shaft 61, which rotates in a counter-clockwise direction (Figs. 1 and 2), the no-reverse pawl 121 will cooperate with the ratchet 120 and during the remainder of the resetting rotation of the reset shaft, the supplementary holding pawl 122 will cooperate with the ratchet 120 whereby to prevent objectionable intermediate reverse rotations of the reset shaft 61 during resetting. After the no-reverse pawl 121 has performed its function of preventing objectionable reverse rotation of the reset shaft, it is moved out of holding position by the ratchet and latched in non-holding position by the latch 126. The purpose of so latching the no-reverse pawl is to hold the herein-after described stop engaging arm 141 in operative position. After resetting and during reverse rotation of the reset shaft, the cam 92 rotates in a counterclockwise direction (Fig. 2), whereupon the nose-shaped cam portion 131 on the cam member engages the pin 130 of the latch member, thus moving the latch to non-latching position. Thereafter, the spring 124 moves the non-reverse pawl 121 to holding position and the stop engaging arm 141 to non-operative position. Further, the spring connected cam 92 will also cause the desired automatic reverse rotation of the shaft 61 and of the several counter shafts 115-118, inclusive, at the end of the resetting operation; this automatic reverse

operation herein being transmitted from the gear 105 through the two intermediate gears 107 and 108 and the several reset operating gears 110—113, inclusive.

Operatively associated with the no-reverse pawl 121 is also means operative during resetting to control the drive gears 18 and 43 of the quantity and cost counter drives, respectively, heretofore described; these means herein cooperating with the blocks 20 and 46 rotatable with these gears and likewise heretofore described. As shown in Figs. 2 and 7a, the no-reverse pawl 121 carries a pin 135 projecting rearwardly through an arcuate slot 136 in the frame 7 and carrying on its rear end a pivoted link 138. This link has a slotted pivotal connection 139 with a pin 140 projecting forwardly from a swinging stop engaging arm 141 pivoted on the shaft 61 on a sleeve 142 carried on the hub 106 of the gear 105. As shown, this swinging stop member 141 is connected by a coiled spring 143 to a suitable abutment on the frame so that it is biased to stopping position and the pin 140 is held in the lower end of the slot 139. Thus, during rotation of the reset operating shaft 61 in a resetting direction and toward the end of the resetting revolution thereof, the link 138 is moved downward, in such manner as to permit the spring 143 to swing the arm 141 about its pivot. This brings the extremities 144 of this arm into the path of the peripherally disposed blocks 20 and 46 rotatable with the gears 18 and 43, respectively, of the quantity and cost counter drives, in such manner as thereby to prevent, in a well known manner, overtravel of these elements of the drive, which also rotate at the end of the resetting operation.

Herein, also, improved means are provided for preventing such rebounding of the gears 18 and 43 as may result from rapid resetting. These means (Fig. 7a) herein include latch members 145 pivoted at 146 near the extremities 144 of the arm 141 and normally biased to latching position by springs 147 having abutments on these extremities. Note here also that the ends of these latch members are disposed in the plane of the extremities 144 of the member 141, and that they carry latch faces 148 parallel to the extremities 144. Also, pins or projections 149 (Fig. 6) are carried on these latch members and engage adjacent side faces of the extremities 144 to limit the latch member movement relative thereto. Thus, when the extremities 144 on the stop arm 141 engage the blocks 20 and 46, the faces 148 of the latch member 145 will engage the opposite faces of the blocks, in such manner as to effectively prevent rebounding of the gears carrying the blocks. Further, it will be evident that, while in the earlier stages of resetting the ends of the latch members 145 will ride on the peripheral portion of the members 21 and 45 carrying the blocks, the rotating blocks will kick out these latches, and thus permit the latches and the arm extremities 144 to engage and hold opposite sides of the blocks in the period just before the pin 98 on the cam 92 drops into the notch 99. Moreover, both the swinging stop arm 141 and these latch members 145 are automatically moved out of engagement with the blocks when the pin 98 drops into the notch 99, as a result of the action of the spring 94 on the cam 92 and the release of the no-reverse pawl 121 by the latch 126 and consequent raising of the link 138 by the pin 135, all of this block releasing movement occurring as the cam 92 and the var- 75

ious counter reset shafts are being moved reversely at the completion of resetting.

Operatively associated with the resetting mechanism and the controlling mechanism therefor is 5 also improved shutter mechanism for the several counter units. This mechanism herein is so constructed and arranged as to effect the operation of the shutters by the resetting mechanism as the reset operating gears 110 to 113 inclusive 10 are operated by the intermediate gears 107, 108; the shutters also being operated in timed relation with the control mechanism in such manner as to be closed at the beginning of the resetting operation and opened after the various counter 15 reset shafts 115 to 118, inclusive, have been moved through their final reverse 45° movement occurring at the completion of resetting. Further, it will be observed that this shutter mechanism herein is such as to enable the several 20 counter units to be removed rearwardly as units at will, from the counter driving and resetting trains, without requiring either the disconnection of any shutter operating mechanism, or the removal of the shutter mechanism as a necessary 25 preliminary to the removal of the counter unit. Also, this construction similarly enables these units to be assembled without requiring any subsequent connection of the shutter operating mechanism, or any subsequent addition of the 30 shutter mechanism before the counter mechanism is ready for operation. Attention is also directed to the fact that I am able to obtain these advantages while providing improved shutters carried on the removable counter units, and also 35 while continuing to time the operation of the shutters with the resetting mechanism, in such manner that the shutters are closed at the beginning of the resetting operation and before the counter number wheels begin to move, and are not reopened until after these wheels have been 40 returned to their zero position.

In this improved construction, it will be noted that each shutter is of the same construction so that a description of the shutter mechanism in 45 connection with a single unit will suffice for all. The left hand cost counter has, accordingly, been used herein for purposes of illustration (Figures 11 to 16). As shown in Figure 15, a shutter 155 is journaled at its opposite ends at 156 on the reset shaft, herein the shaft 115; this shutter being of a generally usual construction and having its pivoted ends journaled just inside the end walls 157 and 157' of the counter unit. However, it 50 will be observed that improved operative connections are provided between the reset operating gear 110 and this shutter. These include herein an aperture 158 in the adjacent operating arm 159 of the shutter and a rearwardly projecting shutter operating member 160 projecting through and fitting this aperture and also movable reversely in a corresponding elongated arcuate slot 161 in the end wall 157' of the counter unit. This member 160 also is connected to the reset 55 driving gear 110 by an improved clutch connection including improved elements acting between the gear 110 and a plate 162 fixed against rotation relative to the end wall 157' and suitably spaced therefrom by spacing and locating posts 163.

Referring more particularly to this clutch mechanism, note that a coiled spring 164 (Fig. 14) is disposed about the journaled portion 165 for the shaft 115 in the end wall 157'. This spring 164 has one free end extending radially and abutting one side of the arm 160 just out-

side the frame 157', while the other end engages one of the spacing posts 168; the spring thus operating to bias the member 160 so that it normally engages the upper end 161a of the arcuate slot 161. As shown in Figures 13 and 14, the reset driving gear 110 is also fixed to a sleeve 166 forming a part of the adjusting mechanism 114, which sleeve also extends through the fixed plate 162 and has the latter connected thereto by a ring washer 167 suitably attached to the sleeve as by upsetting, to produce a unitary construction. Herein, the member 160 is also provided with a depending journal portion 168 journaled on this sleeve 166 between the plate 162 and the gear 110, so that the member 160 may move freely about the axis of this sleeve. Also, the member 160 is provided with a suitable ball receiving aperture 169 near the extremity thereof and between plate 162 and gear 110, this aperture preferably having a hardened bushing 170 therein of substantially the diameter of a ball 171 disposed in this bushing. Here, moreover, note that the diameter of this ball is greater than the thickness of the journaled portion 168 of the member 160 and the space between the gear 110 and plate 162, and that a round countersunk hole 172 is provided at one point in the gear 110 so that in one position of the parts, the ball may interlock the member 160 and the gear 110. Further, a corresponding but oppositely countersunk hole 173 is provided in the plate 162 in angularly offset relation to the hole 172, the angular relation of these holes herein being such that the ball 171 is cammed out of the hole 172 by the latter under the action of the spring 164 and into the hole 173 just before the member 160 engages the lower end 161b of the slot 161.

As a result of this construction, when the reset operating gear 110 is rotated at the beginning of resetting, the shutter 155 is moved therewith into the closed position of the shutter, the ball 171 acting as a positive connecting means during this movement. When, however, the shutter has reached closed position, i. e. as the member 160 reaches the end 161b of the slot 161, the holes 172 and 173 come into registry and the ball is similarly cammed out by the hole 172 to release the member 160 from the resetting gear 110 and moved into the hole 173 in the fixed plate 162. Thus, the resetting gear 110 may thereafter continue to move throughout the remainder of its forward resetting operation, while leaving the shutter locked in closed position. When, however, the gear 110 returns to such a position at the completion of its resetting revolution, that the hole 172 again comes opposite the ball 171, the latter will then be free to be moved, by the action of spring 164 on the member 160 and the camming action of hole 173, into the hole 172, the walls of the hole 173 in the plate 162 then being disengaged. Here note also that this return of the ball 171 into the hole 172, occurs at the completion of the forward resetting movement of the gear 110, so that, as this gear is moved reversely during the reverse 45° movement of the reset shaft 115, the shutter 155 is moved positively into open position; the member 160 then being positively connected to the gear 110 through the ball as just described, while the ball is locked in this position by the plate 162.

The several counter units 1, 1a, 2 and 2a are also of an improved construction enabling the same to be assembled or removed as units while housing the several number wheels thereof and the shutter mechanism. Herein, the end walls

157, 157' are formed on a longitudinally extending connecting portion 175 integral therewith. This portion 175 also is preferably provided with slots 176 (Figs. 9 and 16) in the back thereof and at the opposite ends of the same, to receive, as necessary, the driving gears carried by the unit shafts 26, 27, 51, 52. Further, the end members corresponding to the member 157' also carry on their front faces projecting threaded spacing and connecting member 177, three of these members (Fig. 11) being shown herein spaced radially around the axis of the resetting shaft 115. Also, as shown in Figure 9, these members 177 are received in countersinks 178 in the rear face of the front frame 1 of such depth and diameter as to insure proper location and meshing of the driving and resetting gears, and these members 177 are also connected to the frame 1 by bolts or cap screws 179 extending through and releasable from the front of the frame 1. Attention is further directed to the fact that apertures 180 (Figs. 2 and 9) are provided in the frame 1 into which the front end of the resetting shaft and the adjusting mechanism 114 on each unit extends, so that this mechanism is readily accessible from the front of the frame 1. As a result of this construction, it will be evident that upon removing the bolts or screws 179, the entire counter unit including the shutter and the combined shutter operating and reset operating 110, may be readily withdrawn rearwardly; the counter driving gears and this resetting gear 110 carried by the unit being automatically separable during this rearward movement. Obviously, a unit may be similarly assembled by a forward movement, the countersinks 178 then insuring proper meshing of the several gears.

The counting mechanism proper which is carried in each of the counter units is of a generally well known type including a series of number wheels 181, 182 and 183 coaxially disposed and operatively connected through transfer mechanism, with the counter driving gear connected to the lowest order wheel in a well known manner. Referring to Figure 15, the lowest order wheel 183 has a driving gear 54 fixed on spacing members 184 carried on an inwardly bent face 185 surrounding the wheel axis. This face, in turn, carries on its opposite face a spring connected reset pawl 186 (Figs. 16 and 18) adapted to operate with the resetting groove 187 in the reset shaft 115. In this construction, the pawl 186 is carried in a member 188 constituting a locking disc and having a two toothed gear 189 also cast with this disc; this member 188 being disposed in a chamber 190 formed by the indenting of portion 185. Also, the member 188 is formed integral with a sleeve 191 on which the driving gear 54 is carried.

The second wheel 182 is generally similar as regards the structure of the member 188, pawl 186 and sleeve 191 and the arrangement of these elements, but it will be noted (Fig. 15) that the end of the sleeve 191 is here peaned over at 192, to clamp a holding disc 193. This, in turn, holds in position a pawl carrier 194 (Fig. 19) having a spring pressed pivoted pawl 195 therein, adapted to engage the base 196 of the two toothed gear 189 on the member 188 of the lowest order wheel 183, in such manner as to stop the wheel 182 when this pawl engages the base 196 in the process of resetting. Further, it will be noted (Figs. 15 and 20) that a driven gear 197 is mounted on the hub 191 within the number

wheel 182, and carries on its opposite face, projections 188 carrying spring connected pawls 190, which are, in turn, engageable with stop pins 200 and also cooperate with opposite sides of a ratchet 201 fixed to the hub 181. Herein, the gear 187 with the pawls 190 is rotatably mounted on the hub 181 between the pawl carrier 184 and the ratchet 201, the construction thus being such as to provide with a usual transfer mechanism, a usual clutch connection between the second wheel 182 and the lowest order wheel 183. The connection between the second and third wheels being duplicates of that described between the first and second wheels, further description thereof is unnecessary.

As regards the transfer mechanism between the several wheels, however, it will be noted (Fig. 17) that transfer pinions 202 are rotatably mounted on pinion supporting webs or members 203 disposed in the frame portion 175 and preferably having extensions 204 on their ends receivable in slots 205 in the top and bottom portions of the member 175. Here also corresponding extensions 206 are provided on the back of these transfer pinion supporting members or webs 203, which are received in corresponding apertures 207 in the back of the portion 175. With these members 203 of this construction, it is evident that they may be readily inserted in the member 175 from the front in their proper position to bring their transfer pinions between adjacent number wheels, while it will further be evident that the number wheels may thereafter be inserted in aligned position within the unit casing, whereupon the reset shaft having the unitary clutch connection described above and held in place by the washer 167, may be inserted longitudinally to complete the assembly of the counter mechanism. Here also note (Fig. 15) that the shaft 115 is held in the desired assembled relation by a vertically removable holding clip 208 of usual construction; the latter being bifurcated at its inner end to pass on opposite sides of a reduced portion 209 on the shaft which is within the end frame 157 and between the same and the shutter arm 159, this clip 208 herein also having a bent upper end 210 received in a correspondingly cut out portion in the top of the wall 157.

To permit ready access to the counter mechanism while protecting the same during handling, the counter wheels are enclosed within a sheet metal cover 211 (Figs. 1, 15, 16, and 17) of generally U-shaped cross section and having a generally rounded front end 212 provided with a horizontal slot 213 forming a reading aperture or window. Further, it will be noted that this member 211 is provided with inwardly bent ends 214 at the back which are suitably connected, as by ears 215 (Fig. 1), in corresponding recesses in the back wall of the portion 175. Thus, it will be evident that the counter mechanism will be adequately protected by this member 211, while the latter provides a satisfactory reading window and also is readily disconnected and removable whenever desired, by merely springing out the ears 215, whereupon the parts are readily separated.

It will be understood that as shown in Figure 1, a front cover plate 216 is carried by the frame 7 in such manner as to be readily removable while enclosing the controlling mechanism shown in Figure 2. Herein, this plate is provided with spaced lugs 217 on its bottom received in corresponding slots 218 in the bottom of the frame 75

7, while the upper end of the cover plate is attached to the frame as by a removable nut connection 219. Thus, with the enclosed counter units, a construction is provided in which all of the working parts are adequately protected, while permitting ready access whenever desired, to the internal mechanism.

Attention here is also directed to the fact that an audible signal is herein provided for indicating each gallon counted on the quantity counters, this signal herein also being so connected that it is operated at the completion of resetting. This signal means includes a pin 220 (Fig. 8) on the member 17, rotatable with the gear 18 and projecting rearward from the member 17 into the path of a clapper actuating spring 221 carrying a clapper 222 (Figs. 7 and 10) engageable with a bell 223; the latter being suitably supported on the frame 8 between the same and the left hand quantity and cost counters. By reason of this construction, the rotation of the pin 220 with the gear 18 through a complete revolution, causes the bell to be sounded as each gallon is dispensed, while this gear 18 being rotated during resetting, the bell is also sounded as the operation of resetting is substantially completed.

Attention is particularly directed to the marked facility with which the cost and quantity counter units may be connected and removed in this improved construction. More particularly, whereas, in prior constructions it has been impossible to remove the counter mechanisms as units, or necessary to remove the shutter mechanism before the counter units could be removed, or to disconnect the shutter mechanism from the shutter operating mechanism before the units could be removed, in this construction the units are readily removable without requiring the shutter mechanism or its connections to be manipulated in any manner. Instead, the shutters are carried on the units and form a part thereof, while also being operated by improved mechanism also forming a part of these units and of the resetting mechanism. Further, as a result of this construction, it is made possible to utilize a markedly improved and simplified resetting drive conveniently disposed on the rear face of the front frame, in such manner as to enable the reset driving gears of the several units, which herein are also shutter operating gears, to be moved into or out of mesh with their driving gears on the frame, herein also in the form of improved intermediates each driving an upper and a lower combined resetting and shutter operating gear. Attention is further directed to the fact that while these improvements in the removable units and the shutter operating and resetting mechanisms therefor are made possible, it is also made possible to continue to use an exceedingly simple drive operative during counting and likewise carried at the rear of the front frame member, the counter driving wheels carried on the units also being readily and automatically connected to and disconnected from the drive, as the units are assembled or removed. Thus, all necessity is eliminated for the previously necessary shutter operating connections disposed between the counter driving elements and the resetting train and which previously required connection or disconnection after the units were assembled or before they could be removed. Attention further is directed to the exceedingly compact construction provided.

In Figs. 21 to 28, I have shown a modified form

of controlling mechanism which, while not necessary, is preferred where a pawl construction of the type illustrated in Fig. 18 is employed; this construction being desirable in order to give a reverse resetting movement of 54°, as distinguished from the 45° reverse movement of the resetting shafts, heretofore described. In this construction, the ratchet 225 corresponds closely to the ratchet 120 heretofore described, save that this ratchet 225 is provided with an additional notch 226 between a notch 227 and a nose 228; ratchet teeth 229, 230, 231 and 232 being provided between the notch 227 and nose 228 as in the form previously described. Further, herein the swinging cam 233 corresponds to the cam 92 heretofore described and is similarly mounted on a projecting journal 234, corresponding to the journal 93, and adapted to cooperate with a stop pin 235, corresponding to the stop 96, while the cam member 233 is provided with a like toothed sector connection with the clutch operating arm 89, and also with a spring 84. However, it will be observed that the pin 235 is raised to permit a greater swinging movement of the cam 233, in such manner as to permit the cam 100 to move reversely through an additional 9°, i. e. to have a 54° reverse movement, as distinguished from the 45° reverse movement heretofore described. Inasmuch as only the holding pawl 236, corresponding to the pawl 122, and the latch member 237, corresponding to the latch 126, are the only other elements changed in this construction, it is believed unnecessary again to describe more of the remaining mechanism than these elements 236 and 237. Of these, the pawl 236 is mounted on the frame and connected with a spring as heretofore, but it will be noted that herein this pawl is provided with a lateral extension 238 thereon closely adjacent its pivot and adapted to cooperate with certain of the ratchet teeth in different positions of the parts as hereinafter described, while this pawl is here also provided with an elongated tail portion 239 adapted to engage the edge 240 of the swinging cam 233 in certain positions of the parts as hereinafter described. As regards the latch 237, note also that this is also of the same general construction heretofore described and similarly mounted on the frame, but that in this construction the latch is shorter so that its pin 241 on the end of the latch, is disposed under the nose 242 on the cam 233 in the reset position of the parts.

In the operation of this construction, with the parts at the beginning of resetting in the position illustrated in Figure 21, it will be evident that with the cam 100 rotated in a counterclockwise direction, the parts will pass through the positions shown in Figures 22 to 28 inclusive in the process of resetting; i. e. of returning to the position shown in Figure 21. Referring first to Figure 21, note that the end of the tail 239 on pawl 236 engages the edge 240 of the cam 233, while the lateral portion 238 on this cam clears the nose 228 on the ratchet 225; the pin 241 on the latch 237 then being disposed under the nose 242, as heretofore described. As the cam 100 is rotated counterclockwise, the shutter operating mechanism will be immediately operated due to the rotation of the several reset operating gears 110, 111, 112, 113; the latter gears herein commencing to rotate as the cam 100 starts to move. After a rotation of the latter of approximately five degrees, the clutch shipping mechanism including the shipper 60, is operated through the cam 233 and its connections to the shaft 88,

in such manner as to start disconnection of the movable clutch members 19 and 44. Herein, these clutch members are disconnected from their cooperating clutch members 22 and 47 after approximately fifteen degrees of rotation, but they have a further declutching movement, being in their maximum out position upon approximately 57° of movement of the cam 100.

As the latter rotates from the position shown in Figure 21 to that in Figure 22, the no-reverse pawl 121 has its left hand arm 125 moved down into engagement with the notch 228 on the ratchet 225 in such manner as thereby to prevent reverse rotation of the latter, the tail 238 on the pawl then still engaging the edge 240 of the cam 233. As the parts continue to move into the position shown in Figure 23, it will be observed that the pin 98 on the cam 233 leaves the notch 99 in the cam 100, the cam in this position being free to turn reversely, but prevented from returning to the position shown in Figure 22 by the engagement of the arm 125 with the tooth 230 on the ratchet 225, while the tail 238 in this position of the parts is out of contact with the edge 240 of the cam 233. Note also that the lateral extension 238 in this position rides on the ratchet as it moves from the position in Figure 23 to that shown in Figure 24, and that the lateral extension 238 engages the tooth 227, in such manner as to prevent reversal; the arm 125 of the no-reverse pawl 121 here also engaging the tooth 232.

As the parts move from the position shown in Figure 24 to that shown in Figure 25, the stop arm operating link 138 is operated in such manner as to start to swing the stop arm 141 into the path of the blocks 20 and 46, this stop arm engaging these blocks when the cam 100 has moved through approximately 180°. This occurs when the nose 228 on the ratchet engages the adjacent extremity of the arm 125 of the no-reverse pawl 121, and the latter arm is then swung out of the path of the nose 228 as the ratchet continues to rotate into the position shown in Figure 25; the no-reverse pawl then being latched by the latch member 237, as shown, in such manner as to insure that the swinging member 141 will engage the blocks 20 and 46 at the proper time.

The parts being in this position, as the cam 100 is rotated further toward the position shown in Fig. 26, the lateral extension 238 successively engages teeth 229, 230, 231, and 232 and engages in the notch 226 in the ratchet 225 when in the position shown in Figure 26, all in such manner as to prevent reverse rotation of the cam 100 and any possible return of the ratchet in a clockwise direction to the position shown in Figure 21, while the movable clutch members 19 and 44 are disconnected from their cooperating members 22 and 47. Further, it will be noted that in the position shown in Figure 26, the shutters 155 are ready to be opened through their spring 164, the several shutters starting to clear when the cam 100 has been rotated through approximately 395°. From the position shown in Figure 26, the parts are moved to the position shown in Figure 27, the clutch controlling shipper 60 starting its return movement when the cam 100 has been moved through approximately 404°. The return movement of the cam 233, however, does not start until the cam 100 has moved through 414°, i. e. until the parts occupy the position shown in Figure 27, when the pin 98 is entering 75 the notch 99 under the action of the spring 84.

In this position, the no-reverse pawl 121 is still held by the latch 237, but the pin 98 is moving down into the notch, while the cam 233 is moving toward the tail 238 on the pawl 236 in such manner as to engage the latter and thereby hold out of the notch 228 the lateral extension 238 on that pawl as the parts move toward the position shown in Figure 28.

As the parts are thus moved from the position shown in Figure 27 to that in Figure 28, in a reverse direction, or clockwise, under the action of the spring 94, it will be observed that the reset shafts 115, 116, 117, 118 will be rotated reversely through an angle of 54°, in such manner as to insure the picking up all of the several reset pawls 186 following the next counting operation, irrespective of the position of the counting wheels at the end of that operation. During this reverse movement of the cams 233 and 186, it will also be noted that the movable clutch members 19 and 44 start to engage, this occurring when the cam 186 is still about 15° from its full reset position shown in Figure 21, while the stop arm 141 starts to release shortly thereafter upon the release of the latch 237 which then has its pin moved into releasing position by the nose 242 on the cam 233. However, the clutch members 19 and 44 are not fully engaged until the cam 186 is approximately 5° from the end of its reverse movement. After these clutch members are thus fully reengaged, the latch 237 is thrown out in such manner as to complete the movement of the swinging arm 141 under the action of the spring 124 just before, herein 2° before, the completion of the reverse movement of the cam 186. In Figure 28, it will be observed that the latch 237 is shown just as it disengages the no-reverse pawl 121, at which time the pin 98 is approaching the bottom of the notch 88 in the cam 186 and the pawl 236 is again in contact with the edge 240 of the cam 233, in such manner as to permit the nose 228 to clear the lateral extension 238. Note here also that the connection of the clutch 5° before the end of the reverse movement of the parts, insures that the swinging stop member 141 will not be disconnected before the clutches are reengaged, while the remaining 2° of movement is also such as to insure the release of the blocks 28, 46 by the stop arm 141.

As a result of this construction, it will be observed that it is possible to extend the range of reverse movement of the counter reset shafts 115-118, inclusive, in such manner as, if desired, even more adequately to insure picking up of the reset pawls 186 and their number wheels when the latter are in the "9" position. Further, by reason of the improved holding pawl construction, it is made possible to prevent efforts to cheat, as by rotating the reset shaft reversely when the parts are in the position shown in Figure 26, the holding pawl then preventing the return of the reset shaft to the initial position shown in Figure 21 through the engagement of the lateral extension 238 with the notch 228. In this connection, it will be noted that in this position of the parts, the shutters are partly cleared and the clutches are disconnected, in such manner that, were it not for this new holding pawl construction, an operator might return the reset shaft to its initial position while the clutches remained out and thereafter, either before or after hanging up the nozzle, continue to dispense gasoline while the clutches continued to be disconnected. Such cheating operation while the clutches are disconnected and without registration on the pump, as sometimes occurs where

5 a dishonest operator seeks to furnish gasoline to a friend or himself at the expense of the station, is however rendered impossible by the holding pawl described herein, which makes it impossible to return the reset shaft to initial position while the clutches are thus released and, instead, makes it necessary for the operator once starting to reset, to complete the resetting operation and reconnect the clutches before the pump can again be operated. These and other advantages of my improved construction will, however, be clearly apparent to those skilled in the art.

10 While I have in this application specifically described one form which my invention may assume in practice, it will be understood that this form of the same is chosen for purposes of illustration, and that the invention may be modified and embodied in various other forms without departing from its spirit or the scope of the appended claims.

15 What I claim as new and desire to secure by Letters Patent is:

20 1. In combination, a frame carrying a reset operating train driven in one direction during resetting and means for reversely driving said train at the end of resetting, a counter mechanism on said frame having a shutter and cooperating resetting mechanism including a reset operating gear driven by said train, and shutter operating connections between said gear and shutter for closing said shutter at the beginning of resetting and opening the same as said train moves reversely.

25 2. A counter unit comprising a frame, operatively connected counter mechanisms therein having resetting mechanism including a reset shaft journaled in said frame and a reset driving gear coaxial with said shaft outside said frame, a pivoted shutter inside said frame, and mechanism between said gear and shutter including a shutter operating member extending through said frame and engaging said shutter and means for rotating said member with said gear, disconnecting said gear for further independent rotation, and reconnecting said elements.

30 3. A counter unit comprising a frame, operatively connected counter mechanisms therein having resetting mechanism including a reset shaft journaled in said frame and a reset driving gear coaxial with said shaft outside said frame, a pivoted shutter inside said frame, and shutter operating means between said gear and shutter including a shutter operating member and a detent movable with said operating member and interlocking said member to said gear in one position of said gear and to said frame in another position of said gear.

35 4. A counter unit comprising a frame, operatively connected counter mechanisms therein having resetting mechanism including a reset shaft journaled in said frame and a reset driving gear coaxial with said shaft outside said frame, a pivoted shutter inside said frame, and shutter operating means between said gear and shutter including a shutter operating member biased to shutter open position and extending through said frame and engaging said shutter and rotatable about the axis of said shaft and clutch mechanism for connecting said shutter operating member to said gear, said clutch mechanism being outside of said frame and rotatable about the axis of said shaft.

40 5. A counter unit comprising a frame, operatively connected counter mechanisms therein

having resetting mechanism including a reset shaft journaled in said frame and a reset driving gear coaxial with said shaft outside said frame, a pivoted shutter inside said frame, and shutter operating means between said gear and shutter including a shutter operating member biased to shutter open position and carrying a ball and cooperating normally differently angularly disposed ball receiving recesses carried by said gear and frame.

6. A counter unit comprising a frame, operatively connected counter mechanisms therein having resetting mechanism including a reset shaft journaled in said frame and a reset driving gear coaxial with said shaft outside said frame, a pivoted shutter inside said frame, and shutter operating means between said gear and shutter including a shutter operating member biased to shutter open position and carrying a ball and cooperating normally differently angularly disposed ball receiving means on said gear and frame and movable into registry in one position of said gear.

7. In a counter, a counter unit having operatively connected counter mechanisms therein and resetting mechanism including a reset driving gear outside said unit, a shutter inside said unit, a frame carrying said unit and having resetting mechanism including a gear driving said reset driving gear and means for rotating the latter during resetting and reversely at the end of resetting, and means operatively connected between said shutter and reset operating gear through which said gear positively closes said shutter in the first stages of the resetting movement of said gear and opens said shutter upon reversal of said gear at the end of resetting.

8. In a counter unit, a frame having end members, coaxial operatively connected counter mechanisms therein having resetting mechanism including a resetting shaft journaled in said end members and a resetting gear on said shaft outside one of said end members, a shutter for said counter mechanisms disposed between said end members, and shutter operating

mechanism operatively connected to said gear and shutter and carried on said shaft and longitudinally removable from said frame as a unit with said shaft.

9. In a counter unit, a frame having end members, coaxial operatively connected counter mechanisms therein having resetting mechanism including a resetting shaft journaled in said end members and a resetting gear on said shaft outside

10. side one of said end members, a shutter for said counter mechanisms disposed between said end members, shutter operating mechanism operatively connected to said gear and shutter and carried on said shaft and longitudinally removable from said frame as a unit with said shaft, means normally holding said unit against axial movement and releasable from the exterior of said frame, and a cover on said frame holding said last mentioned means in operative position.

11. A counter unit comprising a frame, operatively connected counter mechanisms therein having resetting mechanism including a reset shaft journaled in said frame and a reset gear fixed to said shaft outside of said frame and rotatable in one direction during resetting and adapted to be driven reversely at the end of resetting, a pivoted shutter inside said frame, and means between said gear and shutter for moving said shutter to operative position during resetting and to move the shutter to inoperative position upon reverse rotation of said shaft at the end of resetting.

12. In a counter, a reset shaft turnable in one direction during resetting and reversely rotatable at the end of resetting, counter wheels on said shaft, a stationary frame member, a gear fixed to said shaft, a shutter having an arm journaled about said shaft and located between said frame member and gear, the opposed faces of said frame member and gear each having a recess, said arm having an opening adapted to register with said recesses, and a clutch ball in said opening.

EDWARD WILD.
